ROTARY HYDRAULIC MACHINE

Aladar Hollander, Berkeley, Calif.

Original application January 20, 1933, Serial No. 652,676. Divided and this application November 6, 1933, Serial No. 696,781

3 Claims. (Cl. 103—96)

This application is a division of my copending application Serial No. 652,676, filed January 20, 1933, which application issued on November 10, 1934, as Patent No. 1,979,622.

5 This invention relates to a rotary hydraulic machine, commonly referred to as a turbulence pump, capable of pumping relatively small quantities of fluid to relatively high pressures.

It is an object of this invention to provide a 10 turbulence pump with a rotary outer casing or rotor having a fluid channel, a stationary inner casing arranged to form a closure for the fluid channel, a piston member carried by the stationary inner casing and positioned to operatively project into the fluid channel, and for providing 15 the inner casing with appropriate fluid inlet and outlet passages communicating with the channel and separated by the piston member.

A further object is to provide the fluid channel 20 with a plurality of blades so as to create, what may be conveniently termed, a relatively rough or fluid-retarding surface for materially increasing the resistance to the flow of fluid therearound in the plane of the channel but which will act 25 to create swirls in the fluid in a direction substantially normal to the circular path of the piston member.

A further object is to arrange the fluid-retarding 30 surface so as to form an operative fluid seal with the piston member.

A further object is to provide the stationary inner casing with bearing means for operatively supporting the rotary outer casing and a stuffing box means operatively associated with the inner 35 and outer casings.

A further object is to provide the inner casing with two diametrically opposed piston members for effectively balancing the unbalanced forces generated within the machine.

40 A further object is to provide this turbulence pump with two stages and to position the single piston member of each stage at 180° apart so as to effectively counterbalance the bending effect caused by the unbalanced pressures of each stage.

45 A further object is to provide a plurality of pumping stages and to angularly position the piston member of each stage with relation to the piston members of the other stages so as to effectively counterbalance the bending effect caused 50 by the unbalanced pressures of each stage.

A further object is to arrange the fluid-retarding vanes or blades in angular relation to the axial plane of the pump.

55 A further object is to provide axial inlet and outlet passages.

Other objects and advantages of the invention will become apparent as the nature of the same is more fully understood from the following description and accompanying drawings wherein is set forth what is now considered to be a preferred embodiment. It should be understood, however, that this particular embodiment of the invention is chosen principally for the purpose of exemplification, and that slight variation therefrom in minor details of construction or arrangement of parts may accordingly be effected, and yet remain within the spirit and scope of the invention as the same is set forth in the appended claims.

In the drawings:

Figure 1 illustrates a sectional view taken substantially in the plane of line 1—1 of Fig. 2, of a single stage double piston turbulence pump, in which the pistons remain stationary.

Figure 2 illustrates a sectional view taken substantially in the plane of line 2—2 of Fig. 1.

Figure 3 illustrates on enlarged scale a fragmental cross-sectional view illustrating a modified form of fluid channel.

Figure 4 illustrates a sectional view taken substantially in the plane of line 4—4 of Fig. 5, of a two-stage turbulence pump in which each rotor is provided with a single piston.

Figure 5 illustrates a sectional view taken substantially in the plane of line 5—5 of Fig. 4.

As will be appreciated from a study of the drawings, the rotary hydraulic machine of this invention is advantageously adaptable for many purposes and uses. In each, the rotary hydraulic machine operates due to the friction or drag created between solid surfaces and fluids, and by causing a relative movement between the retarded fluid and a piston member.

In order to create a maximum friction or drag between the fluid and solid surfaces, the fluid may be confined in an annular channel having an annular opening toward the central axis of the channel, and the three walls thereof roughened or provided with projecting fluid-retarding blades. This fluid friction surface may be conveniently referred to as the rough or retarding surface. The annular opening of the channel may be effectively sealed by a piston-carrying member, and the surface of this member which acts as the closing surface of the channel, may

40 be referred to as the smooth surface. The rough and smooth surfaces are arranged for relative movement, and as the smooth surface acts to counteract the frictional effect of the rough surface upon the fluid, it is important that the ex- 45 50 55

posed area of the smooth surface be reduced to as small an area as is possible. The piston carried by the member projects into the fluid channel and forms with the rough surface an operative fluid seal, that is, during the relative movement between the piston and rough surface, the piston so closely fits the contour of the rough surface that an effective fluid seal is formed between the piston and rough surface, so that leakage past the piston is practically eliminated. An appropriate fluid inlet passage may be formed in the piston-carrying member, and arranged to communicate with the fluid channel at the suction end of the piston, and an appropriate fluid outlet passage may be formed in the piston-carrying member and arranged to communicate with the fluid channel at the discharge end of the piston. Thus fluid may be drawn into the fluid channel at the suction end of the piston acted upon by the rough surface to retard or resist the motion of the fluid relative to the rough surface, and finally forced out of the discharge passage due to the relative motion between the piston and the rough surface.

25 The invention may take the form of a turbulence pump in which the outer casing may be the rotating member, while the inner piston-carrying casing may be the stationary member. This form of the invention is illustrated in Figs. 1 and 2.

30 The term "turbulence" may be used to conveniently distinguish this form of pump from a centrifugal or turbine pump.

35 The turbulence pump illustrated in Figs. 1 and 2, may be of the single impeller double piston type, and may include a frame 1 having central bores 2 and 3 of slightly different diameters, for receiving and supporting the hub 4 of the stationary inner casing 5. The outer end of bore 2 may 40 be closed by the end plate 6 suitably fastened to the frame by means of bolts 7, and the inner casing hub 4 may be clamped to the end plate as by means of the stud 8 and nut 9. An outer casing 10, which in this case forms the rotor of the machine, may be journaled upon the inner casing hub 4, and may be provided with a removable driving flange 11 suitably retained in operative position by means of a nut 12 screw-threaded into the rotor and the locking screw 13. 45 A fluid channel 14 may be formed directly in the rotor 10, but as illustrated in Figures 1 and 2, the channel 14 may be preferably formed in an auxiliary ring member 15, which in turn may be suitably mounted in the rotor as by clamping the 50 channel ring between the rotor 10 and the driving flange 11. A set screw 16 may be provided for locking the channel ring against rotation. The walls of channel 14 may be roughened in any 55 suitable way, as by providing a plurality of equally spaced blades 17. The blades 17 may be cast integral with the channel ring or the channel ring may be slotted and the blades inserted. The blades 17 may be arranged to leave the center portion 18 of the fluid channel unobstructed, in 60 order to permit the pistons 19 to travel therein. The pistons 19 may be of such size as to closely fit the ends of the blades 17 in the center portion 18 of the channel, so as to form therewith a fluid seal, but not so close as to interfere with the travel 65 of the blades past the pistons. The pistons may be formed integral with or suitably fastened to the periphery of the inner casing 5, as by means of rivets 20. The periphery 21 of the inner casing nicely fits the inner diameter of the channel 70 ring in order to form therewith an operative fluid

75 seal, but does not interfere with the free rotation of the rotor. Also to assist in the sealing of the fluid channel, the rotor may be made to closely fit, and thereby form a fluid seal, with each side of the inner casing adjacent the periphery thereof, as at 22 and 23. The peripheral surface of the inner casing which forms the closing wall for the fluid channel, comprises the smooth surface 24 of the channel. The function of the rough surface of the channel is to cause the fluid to 80 rotate with the rotation of the channel, and the greater the area of rough surface to the volume of fluid contained in the channel, the greater will be the effect of the rough surface in driving the fluid, and thus a greater pumping effect will result. As the smooth surface 24 remains stationary, its effect upon the fluid will be to retard the rotation and thus acts to reduce the pumping effect of the machine. It is important, therefore, to provide a maximum of rough surface area and a minimum of smooth surface area, which is accomplished by forming the fluid channel entirely within the rotor, and providing the walls of the channel with the rough surface, and by closing the channel with the smooth surface 24 of the inner casing. The shape of the fluid channel, in cross-section, may be of any desired form, as for example, the channel may be rectangular as illustrated in Figures 1 and 2, or it may be oval, or round as illustrated in Figure 3. In the rectangular form of channel illustrated in Figures 1 and 2, the depth of the channel may be considerably greater than its width, whereby a relatively large, rough surface area is obtainable, while the surface area of the smooth closing wall of the channel will be relatively small, thus the surface area of the rough surface will greatly exceed the surface area of the smooth surface.

85 Fluid may be fed into the fluid channel adjacent the suction or inlet side of the pistons, by any suitable port or passage means, as for example, the inner casing hub may be provided with bore 25 communicating at one end with an inlet passage 26 formed in the frame 1, while the opposite end of bore 25 may communicate with a pair of opposed inlet passages 27 extending through the inner casing, and each having a port opening through the periphery thereof so as to communicate with the fluid channel at a point 90 adjacent the suction end of their respective pistons.

95 The fluid may be discharged through any suitable port or passage means, as for example, a pair 95 of opposed discharge passages 28 may each communicate at one end with the fluid channel at the discharge end of their respective pistons, while the opposite ends of the opposed discharge passages may communicate with an annular passage 29 formed in the hub 4 of the inner casing, which passage in turn may communicate with the frame discharge passage 30.

Any suitable form of stuffing box means 31 may be provided for sealing the bearing end of the rotor against fluid leakage. While the driving disc 11 of the rotor may be suitably connected to a driving means, as for example, the driving disc 11 may be provided with a boss 32 having a tapered bore 33 in which a driving shaft 34 may be secured as by means of the threaded end of the shaft and the nut 35 and locked against slippage by means of key 36. The drive shaft 34 may be driven by an electric motor or other suitable means not shown, and may be supported adj- 75

cent the rotor in a suitable bearing 37 carried by a subframe 38, only partially shown.

As may be observed from Figure 2, the suction and discharge ends of pistons 18 may be appropriately shaped as at 39, to facilitate a smooth entrance and discharge of the fluid being pumped, and in some instances, it may be desirable to extend or overlap the inlet or outlet passages with the end 39 of the pistons. The inner casing may be provided with a single piston 19 having appropriate inlet and outlet passages, in which case the pump would operate to deliver substantially one-half the volume of fluid, but at twice the pressure. However, such an arrangement produces a very undesirable bending moment between the rotor and inner casing, caused by the unbalanced pressures created in the fluid channel. This unbalanced condition of fluid pressure is created by the rotation of the rotor, whereby the fluid received at the suction end of the piston is gradually increased in pressure until the fluid is discharged from the discharge end of the piston. Thus the fluid pressure at the suction end of the piston may be, for the purpose of illustration, at 0 pressure, while at the discharge end of the piston, at a pressure of 100 lbs. per square inch, and therefore, at a point midway between the suction and discharge passages the fluid pressure may be 50 lbs. per square inch. The average fluid pressure from the suction end of the piston to the mid point may be 25 lbs. per square inch, while the average pressure from the mid point to the discharge end of the piston, may be 75 lbs. per square inch, or a pressure difference of 50 lbs. per square inch in favor of the section from the mid point to the discharge end of the piston. And by multiplying the exposed area of the inner casing from the mid point to the discharge end of the piston, by the differential pressure of 50 lbs. per square inch, it will give the resultant unbalanced force which is acting to force the inner casing and rotor apart in a direction from the high pressure section toward the low pressure section, and this unbalanced force causes a bending moment to be created in the shaft and bearings, resulting in undue wear, binding, and besides makes it practically impossible to maintain the stuffing box in condition to effectively seal the rotor against leakage. By the opposed piston arrangement, the fluid pressures are counterbalanced, thus eliminating the unbalanced pressure condition where only one piston is used.

The operation of the pump may be substantially as follows: Fluid supply and discharge pipes may be connected to the pump; the rotor set in motion, and due to the rough surface of the channel, the fluid contained therein will be carried or urged toward the discharge end of the stationary piston; as the fluid moves from the suction port toward discharge port, the rough surfaces of the channel act upon a greater and greater length of fluid, and thus create an increasing rise in the pressure of the fluid until finally the fluid is forced out of the discharge port by the piston at its maximum pressure.

The stationary piston forms an effective operative fluid seal with the rough surface of the fluid channel, and thus effectively reduces the leakage of the high pressure or fluid discharge end of the piston, past the piston to the low pressure or suction end thereof.

The piston, due to its shape, also acts to assist the pressure fluid from the channel into the discharge passage. As the fluid is carried or driven forward, a fresh supply of fluid flows into the

channel from the suction passage, and the piston may be shaped to assist in directing the fluid along a streamline course as it flows from the inlet passage to the channel.

As will be appreciated in this form of turbulence pump, there is created a relative motion between the rough surface and the fluid on one hand and the pistons on the other hand, whereby the pumping action is effected.

When it is desired to pump fluids to a higher pressure than is possible with the turbulence pump of Fig. 1, the length of the rough surface may be increased, which directly increases the pressure output, providing the speed remains constant without increasing the size of the pump. To thus increase the length of the rough surface, the pump may be provided with any number of fluid channels connected in series, as may be necessary to obtain the desired pressure and volume output. In Figure 4 is illustrated a turbulence pump similar to the pump illustrated in Figure 1, excepting that the pump of Figure 4 has been provided with two fluid channels connected in series, or as may be conveniently expressed, a two-stage pump. The two-stage pump of Figure 4 will deliver substantially four times the pressure of the pump of Figure 1, for the same size pump operating at the same speed, because the two channels are connected in series and only a single piston is mounted in each, thus the effective length of the rough surface from suction to discharge, is substantially four times as great as in the case of the single stage pump of Figure 1, in the fluid channel of which two opposed pistons are operatively mounted, thus reducing the length of the rough surface to substantially one-half its total length.

It should be noted however, that these pumps are reversible, that is, the suction and discharge respectively, for one direction of rotation, will become discharge and suction respectively, for the opposite rotation. The pressures produced by the two opposite rotations, may be equal or different, depending upon whether the resistance of the rough surfaces are equal or different for the opposite directions of flow.

The parts of the two-stage pump of Figure 4, which correspond to the like parts of the single stage pump of Figure 1, have been given the same number with the addition of the symbol "a". The principal difference between the single and two-stage pumps, resides in providing a rotor 10a having a greater width, for accommodating a channel ring member 49 having two fluid channels 41 and 42. Each end of the channel ring 49 may be slotted as at 43, to receive the blades 44 for forming the rough surface in the channel. Each of the fluid channels may be operatively closed by one of the inner casings 45 and 46, so as to form a fluid seal with the channel ring. The inner casing 45 may be provided with the piston 47, while the inner casing 46 may be provided with the piston 48. The pistons may be arranged to project into their respective fluid channels and closely fit the edges of the blades 44, so as to form therewith an operative fluid seal for effectively preventing the pressure fluid from leaking past the pistons from the high to the low pressure ends thereof.

Appropriate fluid passages may be provided for serially connecting the fluid channels, which passages may include the inlet or suction passage 26-a formed in the frame member 1-a, to which one end of the hub bore 25-a communicates, while the other end of the hub bore may communicate with one end of the inlet passage 49, 75

which passage may extend through inner casing 46 and through the periphery thereof so as to communicate with the fluid channel 42 adjacent the suction end of piston 48.

5 A discharge passage 50 may be formed in the inner casing 46 and may communicate the fluid channel 42 adjacent the discharge end of piston 48, with a transfer passage 51, which transfer passage communicates with one end of a suction or inlet passage 52 of the inner casing 45. The inlet passage 52 may be formed in the inner casing 45, and extends through the periphery thereof, so as to communicate with the fluid channel 42 adjacent the inlet end of the piston 47, while 10 the discharge passage 53 formed in the inner casing 45, may communicate the fluid channel 41 adjacent the discharge end of the piston 47 with the discharge passage 29—a, and thence to the pump outlet passage 30—a formed in the pump frame member 1—a.

15 In order to counterbalance the unbalanced forces created by the pressure differences in each of the rotors, the pistons 47 and 48 are set 180° apart, so that the unbalanced forces created by 20 the pressure differences of one rotor, will act to counterbalance or neutralize the unbalanced forces of the other rotor.

25 It will be readily appreciated that the pumps of this invention may be utilized as fluid turbines by connecting a suitable source of pressure fluid thereto.

30 It is to be understood that the term "fluid" is to mean any liquid whether easy flowing or viscous, and that the pumps, by properly proportioning the areas of the several parts, may be readily utilized for pumping air, vapor, steam or gas: in other words, may act as a compressor.

35 The invention is not to be limited to the details herein set forth for the sake of illustration, but 40 is of the full scope of the following claims.

I claim:

1. In a rotary hydraulic machine, a frame having fluid inlet and outlet passages, a stationary inner casing having fluid inlet and outlet passages, a cylindrical bearing surface forming a connecting member between the frame and inner casing and having fluid inlet and outlet passages communicating the related passages of said frame and casing, a rotary outer casing journaled upon 45 said bearing surface, a stuffing box forming an 50

operative fluid seal between the frame and outer casing, said outer casing having a fluid channel, piston means carried by the inner casing and arranged to operatively project into the said fluid channel, said inner casing being arranged to 5 form an operative fluid seal for the channel and having its fluid inlet and outlet passages communicating with the channel adjacent the opposite ends of the piston, and means for rotating the outer casing.

2. In a rotary hydraulic machine, a frame having fluid inlet and outlet passages, a stationary inner casing having fluid inlet and outlet passages, a cylindrical bearing surface forming a connecting member between the frame and inner casing and having fluid inlet and outlet passages communicating the related passages of said frame and casing, a rotary outer casing journaled upon said bearing surface and having a fluid channel, a stuffing box forming an operative fluid seal between the frame and outer casing, diametrically opposed piston means carried by the inner casing and arranged to operatively project into the said fluid channel, said inner casing being arranged to form an operative fluid seal for the channel and having its fluid inlet and outlet passages communicating with the channel adjacent the related opposite ends of the piston means, and means for rotating the outer casing.

3. In a rotary hydraulic machine, a frame having fluid inlet and outlet passages, a stationary inner casing having fluid inlet and outlet passages, a cylindrical bearing surface forming a connecting member between the frame and inner casing and having fluid inlet and outlet passages 35 communicating the related passages of said frame and casing, a rotary outer casing journaled upon said bearing surface and having a plurality of fluid pumping channels, a stuffing box forming an operative fluid seal between the frame and outer 40 casing, piston means carried by the inner casing and arranged to operatively project into the said fluid channels, said inner casing being arranged to form an operative fluid seal for the channels and having its fluid inlet and outlet passages 45 serially communicating with the channels adjacent the related ends of the piston means, and means for rotating the outer casing.
